DESIGN FOR A COMBINED HOOD AND CASING FOR A HAIR AND SCALP STEAMER

Floyd V. Schleimer, San Francisco, Calif., assignor to Duart Manufacturing Company, Ltd., Formerly Pacific Hair Goods Company, Ltd., San Francisco, Calif., a corporation of California

Application June 28, 1938, Serial No. 78,118

Term of patent 7 years

To all whom it may concern:

Be it known that I, Floyd V. Schleimer, a citizen of the United States and a resident of the city and county of San Francisco, State of California, have invented a new, original, and ornamental Design for a Combined Hood and Casing for a Hair and Scalp Steamer, of which the following is a specification, reference being had to the accompanying drawing, forming part thereof.

Referring to the drawing:

Fig. 1 is a side elevational view;
Fig. 2 is a front elevational view; and
Fig. 3 is a top view of a combined hood and casing for a hair and scalp steamer, showing my new design.

I claim:

The ornamental design for a combined hood and casing for a hair and scalp steamer, substantially as shown.

FLOYD V. SCHLEIMER.
